MIXING DEVICE

Arthur L. Kurz, Chicago, Ill., assignor to Kurz Company, Chicago, Ill., a copartnership comprised of N. W. Kurz, W. C. Kurz, and A. L. Kurz

Application April 14, 1934, Serial No. 720,604

10 Claims. (Cl. 259—75)

The invention relates generally to mixing or agitating devices and more particularly to power driven devices of this character which are adapted for mixing or agitating liquids.

5 An important object of the present invention is to provide a power driven device of this character adapted to clamp and support a conventional cocktail shaker and to impart thereto an efficient agitating motion for mixing the ingredients contained in the shaker.

Another object is to provide such a device having a support or carriage for the shaker which has an upright position for loading and unloading the shaker and a generally horizontal position during the mixing operation.

Another object is to provide a new, improved and efficient drink mixer, the operation of which tends to arrest interest and thereby stimulate trade.

20 Another object is to provide such a mixing device having convenient and simple means for clamping and unclamping the shaker.

Other objects and advantages will become apparent from the following description taken in connection with the accompanying drawing, in which:

Figure 1 is a side elevational view of a machine embodying the features of the invention, the carrier being shown in its loading position.

30 Fig. 2 is an end view of the device of Fig. 1, with the carrier in its operating position.

Fig. 3 is a side view of the machine with the carrier in its operating position, and illustrating also an alternative form of clamp releasing mechanism.

Fig. 4 is an enlarged fragmental view of a portion of the actuating mechanism.

While I have shown in the accompanying drawing and will herein describe in detail the preferred embodiment of the invention together with one alternative embodiment thereof, it is to be understood that this disclosure is given for the purpose of illustrating the invention and is not intended as a limitation of the invention to the constructions disclosed. In the appended claims, I aim to cover all modifications and alternative constructions falling within the scope of the invention.

In the form chosen for disclosure herein the invention is embodied in a machine having a hollow base 10 upon the top of which an oscillatory holder or carriage 11 of elongated form is mounted to support and oscillate a container such as a conventional cocktail shaker 12. The base 10 is, in the present instance, relatively

large and heavy so as to obviate the necessity for securing the base to the table or standard upon which it rests. Within the base 10, and secured upon the removable bottom plate 13 thereof, is a driving means such as a universal electric motor 14, controlled by a switch 15 on the base, and operable through suitable reduction gearing and other associated connections to impart an oscillating movement to the carriage 11.

The reduction gearing preferably comprises a worm gear 16 mounted in overhanging relation in a bearing 17 on the bottom plate 13 and driven by a worm 18 fixed on the shaft of the motor 14. To the exposed face of the worm gear 16 and eccentrically thereof, one end of an operating link 19 is pivoted by means of a bearing pin 20 so that in the rotation of the gear 16 the link 19 is shifted endwise with a generally reciprocatory motion. The link 19 extends upwardly from the gear 16 and projects through a slot 21 in the top of the base 10 for operative connection with the shiftable carriage 11.

The carriage 11 is preferably constructed and mounted so as to support the shaker 12 in a generally horizontal operating position during the mixing operation (shown in Figs. 2 and 3) and to provide for a generally vertical rest position (shown in Fig. 1) for purposes of loading and unloading. In its operating position, the carriage 11 is preferably rocked back and forth, and an endwise reciprocatory movement is imparted thereto so that the contents of the shaker is dashed back and forth from end to end in the shaker and is efficiently mixed. To obtain this action, the carriage 11 is mounted for pivotal movement about an axis located substantially midway between its ends and a substantial distance laterally of, or beneath the central axis 40 of the shaker 12.

Thus, as shown in Figs. 1 to 3 of the drawing, the carriage 11 has a central bracket 25 with arms 26 extending downwardly therefrom for pivotal connection at their ends with a supporting shaft 27. The shaft 27 is mounted horizontally above the base 10 on standards 28 projecting upwardly from the base. Eccentrically of the supporting shaft 27 the projecting end of the link 19 is connected to the bracket 25 so that the reciprocation of the link imparts a rocking motion to the bracket 25 and the carriage 11.

The connection between the link 19 and the bracket 25 is preferably of such a character as to permit movement of the carriage to its upright

loading position, and to this end present embodiment provides a transverse slot 21 in the link 19 for engagement with a pin 30 on the bracket 25. A spring 31 positioned within the base and acting 5 between the link and the base serves to urge the link toward the pin 30 and thereby preserves the operative relation of the link and the bracket 25.

When the carriage 11 is to be shifted to its loading position of Fig. 1, the link 19 is retracted 10 by the operator against the force of the spring 31 so as to release the carriage. It will be noted that the bracket 25 is so proportioned with relation to the location of the standard 28 that the carriage 11 in its loading position extends downwardly along the end of the base 10.

The carriage 11, in the present instance, is of simple construction and comprises the bracket 25, two laterally spaced parallel rods 35 fixed in the bracket at right angles to the arms 26 and the shaft 27, and opposed clamps 36 and 37 carried by the rods 35 adjacent to their opposite ends for supporting and positioning the shaker 12 thereon. Upon the bracket 25, side plates or 20 positioning arms 38 may also be provided for 25 embracing and engaging the sides of the shaker 12 intermediate its ends to position the parts of the shaker with relation to each other and to the carriage.

Such positioning arms are of particular utility 30 in connection with a shaker of the form herein shown. This shaker comprises a conventional bar glass 12^a and a tapered cover 12^b formed of metal and of a slightly larger size so that it may be clamped over the top of the glass 12^a in tightly 35 sealed relation to the upper edge of the glass.

The clamp 36 is, in the present case, mounted in fixed position adjacent the end of the carriage which is uppermost when the carriage is in its loading position, while the clamp 37 is mounted 40 for longitudinal shifting movement along the rods 35 adjacent to the other end of the carriage. Each clamp preferably comprises a bracket 39 having spaced parallel bores 40 therein through which the rods 35 extend. From 45 each bracket 39 an arm 41 projects in the same direction as the positioning arms 38 to support opposed cup-shaped members 42 which are adapted to fit over the opposite ends of the shaker 12.

50 Thus by slipping clamp 37 along the rods toward the center of the carriage, that is, upwardly from the released position shown in Fig. 1, both ends of the shaker may be embraced to hold the shaker elements 12^a and 12^b together in tightly sealed relation, while the flanges 42^a of the clamp members 42 hold the ends of the shaker against lateral displacement, and the positioning arms 38 maintain the central section of the shaker in position. The inner surfaces of 55 the arms 38 are shaped to a taper which corresponds with the taper of the shaker section 12^b, and as the clamp 37 is applied, the shaker is moved upwardly between the arms 38 until the tapered exterior of the section 12^b is engaged by 60 the arms 38. The clamp 36 is therefore positioned on the rods 35 with due regard for the degree of taper of the section 12^b so as to insure proper functioning of the arms 38 as well as the clamp 36.

70 Preferably the clamp 37 is constantly urged toward its effective position by means such as a contractile spring 45 acting between the bracket 25 and the clamp 37, and means is provided whereby the clamp 37 may be retracted for loading or unloading purposes. In the form shown,

in Figs. 1 to 2, this means comprises a rock shaft 46 journaled in the base 10 and having arms 48 thereon which may, by rocking movement of the shaft 46, be engaged with pins 49 projecting from the opposite sides of the bracket of the clamp 37 to retract the same. Such engagement may take place, of course, only when the carriage is in its vertical or loading position, and rocking movement of the shaft 46 is effected by a handle 50 fixed on one projecting end of the shaft. When the clamp 37 has been fully retracted, the pins 49 engage notches 48^a in the arms 48 so that the retracting force of the clamp spring acts to rotate the arms 48 slightly upwardly until the lower end of the carrier is rotated into abutment with the base 10. This action locks the clamp 37 in its released position.

In the form shown in Fig. 3 two cam plates 55 are fixed at one end of the base 10 in projecting positions wherein the cam surfaces 56 formed by 20 the edges thereof are engaged by the pins 49 as an incident to the movement of the carriage 11 to its loading position. The cam surfaces 56 are so formed that the completion of the downward 25 rocking movement of the carriage serves to shift the clamp 37 to its retracted position. Notches 57 are engaged by the pins 49 when the clamp 37 has been fully retracted so as to maintain this relationship until a positive return motion is imparted to the carriage by the operator.

I claim as my invention:

1. A device of the character described comprising, in combination, an elongated carriage, means for clamping a shaker on said carriage, means supporting said carriage for limited oscillating movement back and forth about an axis extending transversely of said carriage for the purpose of mixing materials in such a shaker, and for other movement to a substantially vertical position wherein such a shaker may be loaded thereon, and means for imparting such oscillating movement to said carriage.

2. A mixing device comprising, in combination, an oscillating carriage, means on said carriage for clamping the sections of a shaker endwise against each other and against transverse displacement with respect to said carriage, spring means urging said clamping means to its effective position with a force sufficient to seal the shaker and hold the same in position, means for opposing said spring means for releasing said clamping means, said releasing means being operable to latch said clamping means in its released relation, and means for oscillating the carriage.

3. A drink mixer comprising a base, a carrier supported on said base for back and forth movement, means on said carrier for engaging and clamping the opposite ends of a shaker to hold the sections of the shaker together and secure the same in fixed relation to the carrier, and means mounted directly on said base and adapted to cooperate with the clamping means on said carrier for releasing said clamping means.

4. A device of the character described comprising a frame, a carrier, clamping means for securing a shaker on said carrier, means supporting said carrier on said frame for movement from a loading position wherein such a shaker is substantially upright to an operating position wherein such a shaker is located substantially horizontal, said supporting means also providing for back and forth movement of said carrier while in said operating position, means for imparting such back and forth movement to said carrier, and operating means for said clamping means

acting automatically to open said clamping means as the carrier is moved to its loading position and to close said clamping means as the carrier is moved from its loading position to its operating position.

5. A device of the character described comprising a frame, an elongated carrier mounted on said frame for movement about a substantially horizontal axis to a loading position wherein said carrier is substantially vertical with one end adjacent one side of said frame, and said carrier also being movable to a limited oscillatory cycle back and forth about said axis to provide an operating stroke in the central portion of which 10 15 the carrier passes through a substantially horizontal position.

6. A device of the character described comprising a frame, an elongated carrier mounted on said frame for movement about a substantially horizontal axis to a loading position wherein said carrier is substantially vertical with one end adjacent one side of said frame, said carrier also being movable back and forth about said axis through an operating stroke in the central portion 20 25 of which the carrier is positioned substantially horizontal, clamps at opposite ends of said carrier for engaging the ends of a shaker to position the same transversely of said axis and spaced laterally therefrom, the clamp which is adjacent said frame when the carrier is in its loading position being shiftable to an unclamped position, and means carried by said frame for operating said clamp.

7. A device of the character described comprising a base, an elongated carrier pivoted intermediate its ends on a horizontal axis, said carrier being shiftable about said axis to a substantially vertical loading position, actuating means carried by said base operable to oscillate said carrier about said axis, said actuating means having a releasable connection with said carrier to permit movement of said carrier to said loading position, clamping means on said carrier operable to secure a receptacle on the carrier, and means

on said base operable as an incident to the shifting of said carrier to its loading position to release said clamping means.

8. A device of the character described comprising a base, an elongated carrier pivoted intermediate its ends on a horizontal axis, said carrier being shiftable about said axis to a substantially vertical loading position, actuating means carried by said base operable to oscillate said carrier about said axis, said actuating means having a releasable connection with said carrier to permit movement of said carrier to said loading position, clamping means on said carrier operable to secure a receptacle on the carrier, and means for releasing said clamping means.

9. A device of the character described comprising a base, an elongated carrier pivoted intermediate its ends on a horizontal axis, said carrier being shiftable about said axis to a substantially vertical loading position, actuating means carried by said base operable to oscillate said carrier about said axis, said actuating means having a releasable connection with said carrier to permit movement of said carrier to said loading position, clamping means on said carrier operable to secure a receptacle on the carrier, resilient means constantly urging said clamping means to its clamped position, and means for releasing said clamping means against the force of said resilient means.

10. A mixing device comprising, in combination, a base, an elongated carriage mounted on said base for oscillation through an operating stroke and for other movement to a substantially vertical loading position, normally closed clamping means on said carriage operable to secure a shaker thereon, and means operable as an incident to the movement of said carriage to its loading position to release said clamping means and to latch said carriage in said loading position with the clamping means released and conditioned for reloading of the carriage.

ARTHUR L. KURZ.
